CLAIM

The ornamental design for a stool, as shown and described.

DESCRIPTION

FIG. 1 is top perspective view of my new stool design;

FIG. 2 is a side perspective view thereof;

FIG. 3 is a another side perspective view thereof;

FIG. 4 is a plan view of a die-cut blank from which the stool is assembled;

FIG. 5 is a perspective view of one embodiment of the internal support of the stool; and,

FIG. 6 is a bottom view of the stool assembled with the internal support of FIG. 5.

The broken lines shown in the drawings are for illustrative purposes only and form no part of the claimed design.
